UNITED STATES PATENT OFFICE.

NEUTON D. RICHARDS, OF LOS ANGELES, CALIFORNIA.

DESIGN FOR A SHOE.

Application filed April 21, 1925. Serial No. 13,182. Term of patent 7 years.

To all whom it may concern:

Be it known that I, NEUTON D. RICHARDS, a citizen of the United States, residing at Los Angeles, in the county of Los Angeles and State of California, have invented a new, original, and ornamental Design for a Shoe, of which the following is a specification, reference being had to the accompanying drawing, forming a part thereof.

Figure 1 is a side elevation of a lady's shoe showing my new design.

Fig. 2 is a top view of the shoe shown in Fig. 1.

Fig. 3 is a front elevation of the shoe shown in Figs. 1 and 2.

Fig. 4 is a rear elevation of the shoe shown in Figs. 1-3.

I claim:

The ornamental design for a shoe, as shown.

Signed at Los Angeles, in the county of Los Angeles, and State of California, this 15th day of April, 1925.

NEUTON D. RICHARDS.

Witness:
